Primary Examiner — Darlington Ly*Assistant Examiner* — Nasim Abdulaziz Ali(74) *Attorney, Agent, or Firm* — LKGlobaL | Lorenz & Kopf, LLP(57) **CLAIM**

The ornamental design for a collapsible table for a vehicle, as shown and described.

DESCRIPTION

FIG. 1 is a front perspective view of a collapsible table for a vehicle showing our new design;

FIG. 2 is a left side elevation view thereof;

FIG. 3 is a right side view elevation thereof;

FIG. 4 is a rear elevation view thereof;

FIG. 5 is a front elevation view thereof;

FIG. 6 is a top plan view thereof; and,

FIG. 7 is a bottom plan view thereof.

The broken lines in the drawings illustrate portions of the collapsible table for a vehicle that form no part of the claimed design. The broken lines illustrating portions of a vehicle show environmental structure that forms no part of the claimed design.
